No. 37,057.

Patented July 26, 1904.

UNITED STATES PATENT OFFICE.

DENNIS B. MARTIN, OF NEW HAVEN, CONNECTICUT, ASSIGNOR TO THE FALCON RUBBER COMPANY, OF NEW HAVEN, CONNECTICUT, A CORPORATION OF CONNECTICUT.

DESIGN FOR SHEET-RUBBER FABRIC.

SPECIFICATION forming part of Design No. 37,057, dated July 26, 1904.

Application filed May 31, 1904. Serial No. 210,580. Term of patent 14 years.

To all whom it may concern:

Be it known that I, DENNIS B. MARTIN, a citizen of the United States, residing at New Haven, county of New Haven, State of Connecticut, have invented a new, original, and ornamental Design for Sheet-Rubber Fabric, of which the following is a specification, reference being had to the accompanying drawing, forming part thereof.

10 The drawing is a representation of my new, original, and ornamental design for sheet-rubber fabric.

What I claim is—

The ornamental design for sheet-rubber fabric substantially as herein shown.

DENNIS B. MARTIN.
